UNITED STATES PATENT OFFICE.

CHARLES E. WEHRENBERG, OF MOUND CITY, ILLINOIS.

BALING-PRESS.

No. 844,068.

Specification of Letters Patent.

Patented Feb. 12, 1907.

Application filed May 7, 1906. Serial No. 315,613.

To all whom it may concern:

Be it known that I, CHARLES E. WEHRENBERG, a citizen of the United States, residing at Mound City, in the county of Pulaski and State of Illinois, have invented a new and useful Improvement in a Baling-Press, of which the following is a specification.

This invention relates to a baling-press, and the object of the invention is a press which will be self-feeding, in which the pressure will increase as the plunger advances into the baling-chamber, and in which the movements will be comparatively slow of those parts in which a high speed is objectionable—as, for example, in a belt or fly-wheel—with at the same time a quick action upon the part of the plunger, thereby giving a greater capacity to the machine by reason of the rapid action of the plunger, and at the same time afford a saving in power by applying the pressure when it is most needed and producing the speed of the driving mechanism.

The invention consists of the novel features of construction hereinafter set forth, pointed out in the claims, and shown in the accompanying drawings, in which—

Figure 1 is a side elevation of my baling-press. Fig. 2 is a plan of the press. Fig. 3 is a detail perspective view of a block-operating lever. Fig. 4 is a side elevation of the plunger and feeder, operating means, a portion of the plunger and of the baling-press being shown in section. Fig. 5 is a detail perspective view showing the block-holder and certain parts connected thereto. Fig. 6 is a section taken through the block-holder, the end of a block being shown in elevation. Fig. 7 is a diagrammatic side view of feeding mechanism.

In these drawings, A represents a truck provided with a baling-chamber B, upon which is arranged a platform B' and a feed-hopper B''. Upon the truck are mounted shafts C, C', and G'. The shaft C carries a belt-wheel D and a gear-wheel E, mounted upon the shaft C'. The shaft C' is provided with a cranked portion F, to which is pivoted a pitman F', bifurcated as shown at F''. A disk G is rotatably mounted upon the truck, being fixed to the shaft G'. This disk rocks back and forth in the bifurcation of the pitman F', and the said pitman is pivotally connected to the said disk. A plunger-rod H is

pivotedly connected to the disk at a point opposite the pivotal point of the pitman F', and the plunger-rod H is pivoted to a plunger H' in the usual manner. A feeder-arm J, also bifurcated, is pivotally connected to the disk G, the bifurcated portion straddling the disk, and adjacent the disk a block J' is arranged between the bifurcated members of the feeder-arm and connected to them and a lug J'', formed upon the periphery of the disk G. A spring J''' is connected at one end to the block J' and at the opposite end to the lug J''. The end of the feeder-arm which works in the hopper B' is provided with the usual feed-block or feeder-jaws J⁴.

To deliver hay to the hopper B', where it can be fed to the baling-chamber by the arm J and jaws J⁴, the following mechanism is employed: A pitman K is pivoted to the gear-wheel E and rocks a pivoted arm K', which arm swings in a guide-bracket K''. The arm K carries a sleeve K⁶, through which passes the cranked shaft K', to the cranked portion of which is pivoted one end of a rod or link K³, while the other end of the said link is pivoted to the rocking arm K'. The opposite end of the shaft K' carries a suitable hay-rake K⁵. A block-holder L is provided with a spring-hinge bottom L', upon which the divisional blocks L² rest. The block-holder is vertically slotted on its front face, as shown at L³. An angled lever M is provided with a sleeve M' at one end, which sleeve is mounted upon the shaft G', and the free end of said lever rests in a guideway L⁴, carried by the block-holder L, and the said guideway communicates with the slot L³. The disk G carries a lug M², adapted to engage the lever M, and a lever N is pivoted upon the block-holder L and bears upon the lever M for the purpose of throwing the same into the path of the lug M².

A curved arm O is carried by the truck-frame and extends above the lever M, and a spring O' is connected to the said lever, and also to the arm O.

The operation of the baling-press is as follows: The disk G is oscillated by the pitman F, and a similar movement is imparted to the plunger-rod H and plunger H'. It will be noted that the pivotal points are so arranged that a short movement of the crank portion F will produce a considerable movement of the pivotal point connecting the disk G and the pitman F' and resulting in a con-

sequent rapid movement of the plunger H' at the commencement of its stroke. As the plunger advances into the baling-chamber the pitman F' and the plunger-rod H will approach the lines of their dead-centers, and the movement of the plunger will become slower as the resistance to compression of the material being baled increases. The hay-rake K⁵, operated from the gear-wheel E, will deliver the hay or other material to the hopper, and it will be forced into the baling-chamber by the feeder-arm J in the usual manner. The spring J³ forms a cushion for the feeder-arm J, so that the same will not become broken should any hard foreign matter be mixed with the material baled. When a sufficient amount of material has been pressed to form a bale and a divisional block is to be inserted, the same is dropped into the block-holder L, where it is held by the bottom L' until the proper time has arrived for its use, and to force it into position into the baling-chamber the lever N is thrown over against the lever M, throwing the same into alignment with the slot L³ and into the path of the lug M², which strikes the lever M and forces it downwardly in the slot, and as the free end of the lever bears upon the block the bottom L' is forced open and the block driven into position.

Having thus fully described my invention,

what I claim as new, and desire to secure by Letters Patent, is—

1. A baling-press comprising a disk, means for alternately giving a partial rotation to the disk in opposite directions, a plunger, a plunger-rod pivoted to the plunger and to the disk, a feeder-arm pivotally connected to the said disk, a spring connecting at one end to said disk, and to the feeder-arm, a block-holder, a lever, adapted to bear upon the block held in the block-holder, a lug formed on the disk adapted to engage said lever, and means for throwing the lever into the path of said lug. 45

2. A baling-press comprising a plunger, a disk, a plunger-rod, pivotally connected to the plunger and to the disk, a feeder-arm pivotally connected to the disk, means for automatically bringing material to be baled into position to be operated upon by the feeder-arm, a divisional block-holder, means for discharging the block from the holder, means carried by the said disk for operating the block-discharging means, and means 50 for alternately giving a partial rotation to the disk in opposite directions. 55
